FLUID DISPENSER

Arthur E. Spencer and Paul B. Hunt,
San Francisco, Calif.

Application April 19, 1939, Serial No. 268,666

3 Claims. (Cl. 226—19)

Our invention relates to the dispensing of fluids from a closed container, such as a bulb.

It is among the objects of our invention to provide means for dispensing a measured quantity of fluid from the container.

Another object is to provide means responsive to the rising level of fluid being dispensed into a receptacle for limiting the quantity of fluid flowing from the dispensing container.

A further object is to provide means for dispensing fluid from a container having resilient walls, such as a rubber bulb, without having to do more than initially squeeze the bulb.

Still another object is to provide means for preventing dripping of fluid from an inverted container after flow has stopped.

The invention possesses other objects and features of advantage, some of which, with the foregoing, will be set forth in the following description of our invention. It is to be understood that we do not limit ourselves to this disclosure of species of our invention, as we may adopt variant embodiments thereof within the scope of the claims.

Referring to the drawing:

Figure 1 is a vertical sectional view of an inverted dispensing device embodying the improvements of our invention. A receptacle into which fluid is being dispensed is also shown in dotted lines.

Figure 2 is a similar view showing a modified apparatus; and

Figure 3 shows the same in tilted position.

Figure 4 illustrates our improvements embodied in a dispensing bulb.

Figure 5 is a cross sectional view of the bulb stem, taken in a plane indicated by line 5—5 of Figure 4.

In terms of broad inclusion, our fluid dispenser comprises a container for holding fluid, a duct for discharging fluid from the container into a receptacle, and a duct for admitting air to displace the fluid in the container and adapted to extend into the receptacle for stopping discharge of fluid when the fluid level in the receptacle rises to the mouth of the air duct. A gauge is also preferably provided for regulating the fluid level to control the quantity of fluid being dispensed. In our preferred apparatus the fluid discharge duct is arranged to form a siphon, and the air duct projects into the space above the fluid in an inverted container. By this arrangement the excess fluid in the siphon duct flows back into the container when discharge has stopped and the apparatus is tilted slightly, thus preventing drip-

ping of fluid from the unit. In a simplified dispenser embodying our invention the fluid container comprises a bulb having walls of resilient material, such as rubber, and the fluid discharge and air inlet ducts extend through the bulb stopper; the ducts being preferably integral to form a unitary stem for the bulb.

In greater detail, and referring to Figure 1 of the drawing, a simple embodiment of our invention comprises a container or bottle 2 of suitable material, such as glass, for holding a supply of liquid 3 to be dispensed. A stopper 4 of suitable material, such as rubber, is provided in the neck of bottle 2 and provides a closure for retaining the fluid when the container is inverted in dispensing position.

An outlet duct 6 of suitable material, such as glass, is provided for discharging fluid from container 2 into receptacle 7, the latter being indicated in dotted lines and representing any receiver for the fluid 8 being dispensed. Discharge duct 6 extends downwardly from the closure to project into receptacle 7, and the upper end of the tube terminates adjacent the inner surface 25 of the stopper. A second duct 9 of suitable material, such as glass, extends downwardly from the stopper alongside duct 6, so that the lower ends of both ducts terminate adjacently. Tube 9 is an air inlet or vent duct for supplying air 30 to displace the fluid discharging from container 2, and this duct extends upwardly from the closure to project into the space above the fluid in the inverted container.

As soon as the bottle is inverted, fluid flows out 35 through duct 6 into receptacle 7 by reason of the inflow of air through duct 9. When duct 9 is closed to stop further inflow of air, the pressure in the space above fluid 3 in the container reduces to a point where discharge of fluid through 40 duct 6 ceases. We depend upon this principle to stop the discharge, and utilize the rising level of fluid in receptacle 7 to seal off the mouth of air duct 9. When the fluid level reaches the mouth of tube 9 the fluid 8 is drawn up into the tube 45 to a height indicated at 11, at which point the column of fluid in tube 9 balances that in tube 6.

In this condition of equilibrium the whole unit 50 may be lifted, and by reasonably careful handling may be carried in inverted position without discharge of fluid. By uprighting the bottle there of course is no danger of discharge, and when the bottle is again inverted the flow starts immediately and continues until the level of fluid 8 again reaches the mouth of air duct 9.

It is thus seen that the extent to which air duct 9 projects into receptacle 1 determines the level at which dispensing will stop, and an operator may therefore control the dispensing action by regulating the inward projection of tube 9 into the receptacle. This is a highly desirable feature, because in instances where the rising fluid level cannot be observed our dispenser automatically cuts off the flow at a predetermined level.

Vent tube 9 is preferably of smaller diameter than discharge duct 6 because a small vent passage is sufficient to supply adequate air. Also a small vent passage offers greater resistance to upward flow of liquid therein, and therefore less fluid is required in the vent duct to balance the column in discharge duct 6. Furthermore, the resistance of a small vent passage to liquid flow effects a more stable balance when the dispenser is removed from the receptacle, thereby making accidental discharge of fluid less likely.

Figures 2 and 3 show a modified arrangement embodying additional improvements. In this case a container 12, vent tube 13 and stopper 14 are provided as in the previous construction. Discharge tube 16 is modified however and projects upwardly into the container with a portion 17 looped back to form a siphon. Also, another tube 18 is provided in the stopper and is connected with a bulb 19 having walls of resilient material, such as rubber. This bulb provides means for increasing the pressure in the container to start the siphon, and may also be used to draw a supply of fluid into the container.

Once the siphon has been started by a slight squeeze of bulb 19 it continues to run in accordance with ordinary siphon principles. The fluid flowing out is displaced by air flowing in through vent duct 13, and as long as the air inflow is not interrupted the siphon will continue to discharge fluid 21 from the container. However, when fluid level 22 closes the mouth of duct 13 the air is cut off and fluid is drawn up into the vent duct to a height such as indicated at 23 where the columns of fluid in the two ducts are balanced. The unit may now be lifted without further discharge of the fluid.

An important feature of this siphon arrangement is that subsequent tipping of the unit from the vertical causes the fluid in discharge duct 16 to be drawn back up into the container so that the siphon will not start unless bulb 19 is again compressed. Figure 2 shows a fluid head x above the inner end of the siphon when the fluid columns are balanced. Figure 3 illustrates the unit tilted from the vertical, and shows that the fluid head x has shortened. This differential upsets the balance and since the pressure above the fluid in the container is below atmospheric, the fluid in duct 16, having less resistance to flow than that in small vent tube 13, is drawn back into the container. Figure 3 shows the lower end 24 of the fluid column in duct 16 after it has started moving upwardly.

We have found that the fluid in duct 16 is drawn up rapidly once the conditions of equilibrium are upset, and that slight tilting of the container in any direction will start the up-flow. After the fluid in duct 16 has discharged back into the container, any further discharge of fluid is positively prevented until bulb 19 is again compressed to start the siphon. The container may therefore be carried inverted with safety and no amount of shaking or jarring will cause discharge.

Figure 4 shows the principles of Figure 2 embodied in a more compact construction wherein a rubber bulb 25 functions as the fluid container. In this case we preferably provide an integral stem 26 having duct passages 27 and 28. Passage 27 forms the air vent, and passage 28 in the fluid outlet, the latter being doubled back at the top to form a siphon. Stopper 29 is also integral with the stem and has a peripheral flange 31 for interengaging the grooved neck of the bulb. The stem and stopper unit may be formed from any suitable material, such as Bakelite.

Such a device looks like an ordinary syringe as used for supplying water to storage batteries. In fact, our dispenser well serves this purpose. Fluid is drawn into the bulb in the usual manner of filling a syringe, and when discharge is desired the bulb is squeezed slightly to start the siphon. Once the siphon is started no further squeezing of the bulb is necessary, as is required in the ordinary syringe.

By inserting stem 26 to the proper level in the receptacle, such a battery, the fluid in the receptacle will rise to the desired level and automatically stop the discharge. This is an important feature in supplying fluid to a receptacle where it is difficult to see and gauge the fluid level. When the unit is removed from the receptacle, the movements accompanying removal cause the excess fluid in duct passage 28 to flow back in bulb 24, and therefore there is no danger of accidental discharge or dripping.

As a further feature we provide a gauge bar 32 on stem 26 to control the depth to which the stem may be inserted into a receptacle. This bar may be molded in fixed position as an integral part of the stem for special uses, as in filling batteries, where water is introduced to bring the electrolyte up to a certain predetermined level in all cases. For purposes of adjustment however we prefer to mount gauge bar 32 on a sleeve 33 slidable along the stem. As shown in Figure 5, a set screw 34 on the sleeve is provided to lock the gauge at a selected height.

For additional flexibility in the use of the dispenser unit, we also pivot gauge bar 32 on sleeve 33 by a screw 35 so that stem 26 may be tilted to facilitate insertion of the latter into a receptacle. By tightening up screw 35 the gauge bar is held fixed in a selected inclined position. This allows the gauge bar to lie flat on the mouth of a receptacle while the stem is tilted. For example, in filling batteries the inaccessible location of the battery in an automobile is often such that insertion of stem 26 at an angle is required.

Our fluid dispenser has many other useful applications, particularly for the introduction of fluids into receptacles having opaque walls and small inlets where it is impossible to see the fluid level in the container. Our dispenser solves this problem by automatically filling the receptacle to a predetermined level. The improved dispenser units are also useful for introducing measured quantities of different fluids into a receptacle when fluid mixtures are being compounded. Thus, one fluid may be introduced to a predetermined level as determined by a given setting of gauge 32. Another fluid may then be introduced to a predetermined higher level by a different setting of gauge 32 on the same or another dispenser unit. Because of the sensitivity of the cut-off action, our dispenser unit provides means for accurately compounding the fluids.

Another advantage of the dispenser is found in the handling of acids and alkalies, where dripping of the fluid from a dispenser after withdrawal from a receptacle is highly undesirable. Our unit with the fluid suction action in the discharge duct positively prevents accidental discharge of fluid, even though the dispenser is moved violently about in the inverted position.

We claim:

1. A fluid dispenser comprising a resilient bulb for holding fluid, a siphon for discharging fluid from the bulb and having its looped portion lying wholly within the bulb, and an air vent for the bulb.
2. A fluid dispenser comprising a resilient bulb for holding fluid, a closure for the bulb, a pair

10 of ducts depending from the bulb through said closure, one of said ducts providing a fluid outlet and the other providing an air inlet, the upper portions of the fluid outlet duct being looped back within the bulb to form a siphon.

5 3. A fluid dispenser comprising a resilient bulb for holding fluid, a closure for the bulb, a pair of ducts depending from the bulb through said closure, one of said ducts providing a fluid outlet and the other providing an air inlet, the upper portions of the fluid outlet duct being looped back within the bulb to form a siphon, and the upper portions of the air inlet duct projecting into the air space above the fluid in the bulb.

ARTHUR E. SPENCER.
